Primary Examiner — Cynthia Ramirez*Assistant Examiner* — Gino Colan(74) *Attorney, Agent, or Firm* — Seager, Tufte & Wickhem, LLP(57) **CLAIM**

The ornamental design for a composite pallet, as shown and described.

DESCRIPTION

FIG. 1 is a front left perspective view of a composite pallet showing our new design;

FIG. 2 is a front elevation view of the design of FIG. 1; FIG. 3 is a left side elevation view of the design of FIG. 1; FIG. 4 is a right side elevation view of the design of FIG. 1; and,

FIG. 5 is a top plan view of the design of FIG. 1. The dash-dash broken lines in the figures represent environment in which the claimed design may be embodied and form no part of the claimed design.

The dot-dash broken lines in the figures immediately adjacent the solid lines represent a boundary between claimed and unclaimed subject matter and form no part of the claimed design.

1 Claim, 3 Drawing Sheets(56)
